UNITED STATES PATENT OFFICE.

AUGIE L. HANSEN, OF CHICAGO, ILLINOIS.

DISPLAY RACK.

Application filed June 17, 1927. Serial No. 199,434.

This invention relates to improvements in display racks, and more particularly to racks of the pedestal type with adjustably swinging rods for the display of goods best shown by 5 draping or hanging, such as piece goods, needle work, linens, table coverings, and the like.

The object of the invention is to provide a 10 novel construction for display racks calculated to embrace such desirable features as simplicity and strength of construction, convenience of assembly and adjustment, and adaptability to different classes of goods and places where the goods are displayed.

15 A preferred embodiment of the invention is disclosed in the accompanying drawing, in which—

Figure 1 is a perspective view of the complete rack with the rods evenly distributed in 20 a semi-circle.

Figure 2 is an enlarged detail view in vertical section through the head of the rack.

Figure 3 is a top plan view of the head with the cap and some of the rods removed; 25 and

Figure 4 is a perspective view of one of the rods.

The rack comprises in general a pedestal 1 having a head 2 at its upper end from which 30 a plurality of horizontal swinging rods 3 radiate. The pedestal stands at a height of about two feet and the rods extend outwardly about the same distance from the pedestal, although their dimensions may vary for racks 35 of different sizes. The pedestal consists of a solid rod 4 extending through a square wooden base 5 surrounded by a large circular metal cap plate 6, the exact construction of the base being a matter of choice in design.

40 The head 2 is detachably mounted at the end of the pedestal and is preferably of solid metal body 7 of inverted cone or bell shape, having a socket 7^a fitting the end of the rod 4 and held by a thumb screw 8. The top

45 surface of the body 7 provides a circular bearing surface for the rods 3, and has an elevated sector 9 of less than a semi-circle and forming a straight shoulder 9^a coinciding with an imaginary chord spaced from the center of 50 the circular bearing surface and of a height substantially equal to the diameter of the rods 3. This shoulder 9^a in the normal position of the rack faces forwardly so that the elevated sector may be regarded as being at

55 the back thereof. At the center of the sup-

porting face is a boss 10 with a tapped hole 10^a extending downwardly therein, and around this base are grouped a series of holes or sockets 11. Considering the arrangement of these holes with reference to a line perpendicular to the shoulder 9^a and passing through the center of the boss 10, they will be found to be grouped in pairs symmetrically on either side of this line, as shown in Figure 3. One pair lies adjacent to the shoulder 9^a behind the boss 10; another pair further outwardly on opposite sides and slightly behind the boss; another pair on either side and near the boss; and still another pair close to and slightly forward of the boss.

70 The rods 3 have one of their ends bent at right angles to form short arms 3^a which fit into the sockets 11 and permit certain of the rods to swing, there being one pair which is preferably held against swinging movement, this being the rearmost pair which extends outwardly in opposite directions parallel 75 with the shoulder 9^a, and held against swinging by stop pins 12 inserted into the face of the supporting surface just in front of the rods. The remaining rods, however, are free 80 to swing within arcs limited by contact with the other arms. Thus the three corresponding pairs of arms on each side of the rack (considering the shoulder 9^a as defining the 85 back) have relatively free swinging movement in an arc somewhat more than 90°, so that it is possible to arrange the rods uniformly as the spokes of a wheel or with an irregular angular spacing by swinging the 90 loose pairs of rods to any desired position within their normal arc of movement.

95 Surmounting the rod supporting head is a semispherical cap or dome 13 bearing throughout a portion of its periphery against the elevated portion 9 of said head, the remaining portion of its periphery being spaced from the lower or depressed surface of the head and forming therewith a curved slot 14 through which the rods project and swing for the purpose of adjustment. The cap is removably held in place by a cap screw 15 extending vertically through its center and anchored in the tapped boss 10. By tightening the bolt, the edge of the cap is held tightly against the rods to hold them against free swinging movement, and by loosening the same, the rods can be readily adjusted to any desired angle.

100 The rack as thus constructed and assem-

bled is suitable for use in windows, counters or in display cases, the rods being swung to any desired position to display the goods in the most effective manner.

5 I claim as my invention:

1. A display rack comprising a pedestal, a head mounted at the end of said pedestal and having an upwardly facing bearing surface, a portion of said surface being elevated 10 to provide a sector of less than a semi-circle having a straight shoulder, a plurality of rods having their inner ends bent at right angles for insertion in sockets formed in the depressed portion of said bearing surface and grouped around the center thereof, a boss at 15 the center of said bearing surface, a cap surmounting said head and bearing throughout a portion of its edge on the elevated portion of said bearing surface, the remaining portion 20 of its edge forming with said bearing surface a guide slot for said rods, and a cap screw extending through said cap and anchored in said boss.

2. A display rack comprising a pedestal, 25 a head mounted at the end of said pedestal and having an upwardly facing bearing surface, a portion of said surface being elevated to provide a sector of less than a semi-circle having a straight shoulder, a plurality of rods having their inner ends bent at right 30 angles for insertion in sockets formed in the depressed portion of said bearing surface and grouped around the center thereof, two of 35 said rods being held against swinging movement against said shoulder, and a cap sur-

mounting said head and bearing throughout a portion of its edge on the elevated portion of said bearing surface, the remaining portion of its edge being spaced from said depressed portion of the bearing surface and 40 forming therewith a guide slot for the swinging rods.

3. A display rack comprising a supporting member having an upwardly facing annular bearing surface at its top, a portion 45 of said bearing surface being elevated, a plurality of rods pivotally mounted at their inner ends on the depressed portion of said bearing surface, and a cap adjustably mounted with said head and having a portion of 50 its edge bearing on the elevated portion of said bearing surface and a free edge portion bearing upon said rods.

4. A display rack comprising a supporting member having an upwardly facing annular bearing surface at its top, a portion of said bearing surface being elevated and forming a straight shoulder, a plurality of rods having their inner ends pivoted in sockets in the 55 depressed portion of said bearing surface, a cap member mounted on said supporting member and having a portion of its edge bearing on the elevated portion of said bearing surface and the remaining edge portion having frictional contact with said rods, and 60 means for adjusting said cap.

Signed at Chicago, Ill., this 10th day of June 1927.

AUGIE L. HANSEN.
